UNITED STATES PATENT OFFICE.

GEORGE E. DALBEY, OF EAST BERLIN, AND THOMAS P. HANFORD, OF BERLIN, CONNECTICUT, ASSIGNORS TO THE STANLEY CHEMICAL COMPANY, OF EAST BERLIN, CONNECTICUT, A CORPORATION OF CONNECTICUT.

METHOD OF TREATING IMPURE LEAD AND LEAD ALLOYS.

No Drawing.

Application filed January 14, 1927. Serial No. 161,237.

This invention relates to a method of treating impure lead and lead alloys.

More particularly the invention relates to a method of removing metallic impurities such, for example, as tin and antimony. These metals also exist in lead alloys and it is to be understood that the term impure lead is intended to include lead alloys.

It is an object of the present invention to provide an economical method of treating impure lead to remove the impurities referred to so as to reclaim commercially valuable products.

With this general object in view, the invention consists in the method which is herein-after described and then more particularly pointed out in the claim.

In carrying out the method of the invention, any given metallic impurity combined with the lead is removed by causing the impurity to replace the metal contained in the acid radical in a salt having an alkali metal as a base. That is, the impure lead is treated with an alkali salt of a metal which, by reason of preferential chemical affinity, is capable of being reduced to a metallic state by one or more of the metallic impurities, whereby the reduced metal is replaced in the alkali compound by the impurity or impurities to be removed.

For convenience of description sodium compounds are used as an example of the alkali salts referred to and the particular salt used depends on the metallic impurity to be removed. For example, for an impure lead in which the impurity to be removed is antimony, the salt used is sodium plumbate or plumbite. In this case the reaction causes the lead of the sodium plumbate to be reduced to metallic lead, the antimony replacing it in the sodium compound to form sodium antimonate. Similarly, when tin is the impurity to be removed, the salt used is sodium antimonite or antimonite. In this case the antimony of the salt is reduced to metallic antimony and the tin replaces it in the sodium compound, forming sodium stannate.

The reactions described may be properly carried out under various conditions. For example, finely divided particles of lead having antimony as an impurity may be brought into contact with a water solution of sodium plumbate or sodium plumbite. Eventually the lead of the sodium salt is reduced to metallic lead and the antimony re-

places the lead in the sodium compound, forming sodium antimonate. Similarly impure lead having tin as its impurity may be brought into contact with a water solution of sodium antimonite or antimonite.

As a result of the reactions referred to the metallic lead or antimony is precipitated as a sludge which may be separated by mechanical means and further treated as desired. There remains a solution containing one or more sodium salts. This solution may be further treated to reclaim valuable products, for example, by the method disclosed in a copending application filed of even date herewith, Serial No. 161,236.

If desired, the impure lead may be treated in a molten condition. In this case, the sodium-metallic salt or salts used may be brought into contacts with the molten impure lead through the medium of fused caustic soda. Upon the reactions above described, there results a molten alloy and one or more sodium salts. Both products may be further treated for the reclamation of values. The molten alloy may be treated, for example, in accordance with the method disclosed in our copending application filed May 4, 1926, Serial No. 106,726. The salts may be treated, for example, according to the method disclosed in application Serial No. 161,238 above referred to.

While tin and antimony have been referred to as metals to be removed from impure lead, it is to be understood that other metals found in impure lead may be removed according to the present invention. The replacements of the metals in a sodium-metallic salt by metals in the impure lead take place in accordance with the preferential chemical affinity for the position of the element forming acid radical of the alkali salt.

What is claimed is:

The method of recovering valuable products from impure lead containing tin and antimony, which comprises treating the impure lead with a sodium-antimony salt and causing the antimony in said salt to be reduced to metallic antimony and the tin in the impure lead to replace the antimony in said salt, forming sodium stannate.

In testimony whereof, we have hereunto set our hands.

GEORGE E. DALBEY.
THOMAS P. HANFORD.

CERTIFICATE OF CORRECTION.

Patent No. 1,693,639.

Granted December 4, 1928, to

GEORGE E. DALBEY ET AL.

It is hereby certified that error appears in the printed specification of the above numbered patent requiring correction as follows: Page 1, line 70, for number "161,236" read "161,238"; and that the said Letters Patent should be read with this correction therein that the same may conform to the record of the case in the Patent Office.

Signed and sealed this 15th day of January, A. D. 1929.

(Seal)

**M. J. Moore,
Acting Commissioner of Patents.**
